IDLING CONTROL FOR TWO-CYCLE ENGINES

Warren C. Conover, Waukegan, Ill., assignor to
Outboard, Marine & Manufacturing Company,
Waukegan, Ill., a corporation of Delaware

Application October 3, 1951, Serial No. 249,528

3 Claims. (Cl. 123—117)

1

This invention relates to an ignition control for regulating the idling of an unloaded two-cycle engine.

The control is desirably effected by means of a cutout switch responsive to manifold pressures and has particular utility in the case of a multiple cylinder, two-cycle engine where at least one cylinder is permitted to continue to fire without interruption. However, the invention may also be used to cut off completely the ignition to all cylinders until the vacuum in the intake manifold drops to the level requisite for maintaining proper operation.

Two-cycle internal combustion engines are ordinarily controlled as to speed by retarding the ignition as well as throttling mixture intake. Such engines are used in outboard motors having clutches for interrupting the drive between the engine and propeller. Such an engine, with throttled carburetor and retarded ignition will ordinarily run consistently at low engine speeds, with or without a load. However, if such an engine is operating without load, there are circumstances under which its speed controls will not maintain it at idling speeds and all control of the engine either by throttling the carburetor or by retarding the ignition may be lost. When this happens, the engine may attain dangerously high and uncontrolled speeds. It has been found necessary to stop the engine by cutting off the ignition or by completely closing the throttle, and then restart. This phenomenon is notable principally in engines of high power, in which internal friction represents an increasingly minute factor.

Invariably the wild uncontrollable condition of the engine is associated with no load and a high degree of manifold vacuum. The manifold vacuum increases with a decrease in load and an increase in engine speed.

While the precise reasons for this phenomenon are not all clear, it appears likely that with a high manifold vacuum, the small amount of new charge pumped through the engine per cycle is insufficient to scavenge the engine cylinders. Several cycles are required to attain a combustible charge in the cylinder, and when ignition finally does occur the charge is still so diluted with inert gases that the flame lingers in the cylinder to prematurely ignite the succeeding charge. This operates like an advanced spark to sharply accelerate the engine, further increasing the manifold vacuum. In any event, an objectionable and previously uncontrolled tendency to operate at excessive speeds when free of load

2

has been observed in high powered engines of this type.

Since the phenomenon is closely related to excessive manifold vacuum, I have found it possible to control the engine by means of a vacuum-operated switch which short-circuits the ignition to at least one of the engine cylinders until the vacuum is restored to normal. The short-circuiting of one or more cylinders attacks the problem in two ways, first, by reducing the engine power and, secondly, by introducing a load factor attributable to the fact that the power of the remaining cylinder or cylinders must be exerted to operate the piston and compress gas in the inoperative cylinder or cylinders.

While the invention really involves a very few added parts, the accompanying drawings show a typical outboard motor assembly in order to illustrate generally conventional parts with which the invention is indirectly concerned.

In the drawings:

Fig. 1 is a view largely in vertical axial section through an outboard motor embodying the invention.

Fig. 2 is a view partially in horizontal section through the power head at the level of the fly-wheel magneto, to which has been added a diagrammatic showing of the control arrangement here involved.

Fig. 3 is a fragmentary detail view similar to Fig. 2 and showing a slightly modified arrangement.

The conventional outboard motor as shown in Fig. 1 comprises an engine or power head A mounted at the upper end of an upright strut B which is carried by the transom bracket C and supports a gear housing D in unitary connection with the power head.

The power head comprises a crank case 1 in which there is rotatably mounted a crank shaft 2 connected by rods 3 and 4 with pistons 5 and 6 reciprocable in cylinders 7 and 8 respectively. The cylinders have spark plugs 9 and 10 for the ignition of the charge delivered thereto from the crank case 1 according to the usual two-cycle principle.

The charge is admitted to the crank case subject to the control of a reed valve 11 from a carburetor 12 through a manifold 13. In the manifold passage 14 of the carburetor is a throttle valve 15.

The engine crank shaft 2 has a drive shaft extension at 16 through the strut B to the lower unit gear case D, where the drive shaft carries a driving gear 17 meshing with driven gears 18

and 19 which are coaxial with the propeller shaft 20. The propeller shaft is rotatably mounted in the gear housing and extends therefrom to support the propeller 21. Splined to the propeller shaft is a clutch sleeve 22 adjustable from the neutral position in which it is shown in Fig. 1 into engagement with the jaw clutches of the driven gears 12 or 19 alternatively, whereby the propeller may be operated in forward or reverse.

The exhaust gases from both of the cylinders 7 and 8 pass downwardly through a common exhaust passage 24 to an outlet such as that shown at 25 which is normally submerged during water operation and may conveniently be built into the rear of the anti-cavitation plate 26.

Ignition is by the conventional flywheel magneto, wherein a magnet-carrying flywheel 28 at the upper end of crank shaft 2 is rotatable with respect to suitable cores and coils mounted on the timing plate 29, the latter being angularly adjustable for timing. Separate coils 30 and 31 and separate breaker mechanisms 32 and 33 are desirably provided for the respective spark plugs 9 and 10.

In conventional magneto operation, each of the magneto coils comprises a primary and a secondary. The secondary is normally connected between a spark plug and ground. The primary coil has one end grounded and the other end connected to the insulated breaker point 33 as best shown in Fig. 2. As the magnetic flux developed in the rotation of the flywheel magnet approaches a peak, the circuit through the coil 31 is closed by the operation of a crank shaft cam 34 upon the breaker arm 35 to allow the grounded contact 36 carried by such arm to engage point 33 under the bias of the spring 37 to which such arm is subject. At or about the peak of the flux, the cam oscillates the breaker arm 35 in a direction to disengage point 36 from point 33, thereby breaking the circuit through coil 31, the break inducing a sharp surge of current in the secondary to cause a spark at the plug with which the secondary is connected.

Any means of preventing such a spark from occurring will suffice for the purposes of the present invention, provided such means may be controlled to become effective whenever the engine idling speed becomes excessive. This never happens except when the engine is free of load, at which time the throttle valve 15 is invariably closed or nearly closed in the manifold passage 14. Consequently, whenever the engine speed becomes excessive, there is a high vacuum in passages 13 and 14 of the manifold.

I utilize this circumstance to effect control of ignition. I provide a vacuum duct 38 leading to the vacuum chamber 39 in a housing 40 which, for convenience, I mount at the front of the crank case. The chamber is subdivided by a flexible diaphragm 41 reenforced by a pair of disks 42 and 43 connected through the diaphragm by a rivet and contact button 45. At least the disk 43 is metallic in order to provide an electrical connection between the contact rivet or button 45 and the housing 40 through the compression spring 46 which normally maintains the diaphragm retracted in a position such that the contact 45 is out of engagement with an insulated contact 47 constituting the head of a bolt 48 supported by dielectric grommets 49 and 50 from the inner and outer ends of a bore 51 with which housing 40 is provided. The threaded outer end of the bolt serves as a binding post to which nuts 52 and 53 are applied. The nut 52 bears against

the grommet 50, while the nut 53 anchors the terminal 54 of a ground wire 55 extending to the insulated breaker point 33 to which the lead 56 from coil 31 is connected in the manner above described.

The chamber 57 at the opposite side of the diaphragm 41 in housing 40 is vented to atmosphere through a duct 58.

During normal engine operation, with the throttle valve 15 at least partially open, the absolute pressure in the manifold between the carburetor and the crank case will be at least relatively high. In terms of vacuum, there will be a low vacuum in the manifold during normal operation. The pressure communicated through the vacuum line 38 to the chamber 39 of housing 40 will be inadequate to overcome the pressure of spring 46 which normally maintains the contact 45 in the retracted position in which it is shown in Fig. 2.

However, when the engine is to idle preliminary to the disengagement of clutch 22, the throttle valve will be substantially closed, leaving just sufficient air for engine operation under these conditions. With the clutch disengaged, the engine has almost no load other than its internal friction and it tends to build up an excessive speed notwithstanding that the throttle valve is practically closed and the spark retarded by the usual oscillation of the timer plate 29 to spark-retarding position. Under these conditions, excessive vacuum in the manifold passages 13 and 14 will be communicated through the vacuum pipe 38 to the vacuum chamber 39 of housing 40 and the pressure differential to which the diaphragm 41 is then subject will overcome the bias of spring 46 to engage contact 45 with contact 47, thus shorting the coil which energizes one of the spark plugs.

Fig. 1 and Fig. 2 show means for rendering only one of the spark plugs inactive. Fig. 3 shows an arrangement in which each of the breaker mechanisms for the respective coils is provided with its own vacuum-operated shorting switch, branches 59 and 60 of the vacuum line 38 being extended into the respective vacuum chambers 39 of the respective housings 40 so that both of the contacts 45 will be simultaneously engaged with contacts 47 to short both of the coils through their respective short circuiting lines 61, thus rendering both cylinders inactive.

In either case, the cylinders will resume activity as soon as the motor slows down sufficiently so that the bleeding of air through the throttle valve will relieve the excessive vacuum. However, if all of the cylinders are simultaneously shorted out of operation, unburned mixture will be discharged from the cylinders into the exhaust passage 24 where it will explode or burn when the cylinders may resume operation. Since the combustion of any large quantity of mixture in the exhaust passage is undesirable, it is preferred to leave one cylinder in operation to dilute and scavenge these gases as rapidly as they accumulate in the exhaust passage, thereby tending to prevent any combustion at this point, or at least to cause the gases to burn harmlessly and non-explosively. Thus, in a multi-cylinder engine, it is preferred to use the arrangement diagrammatically illustrated in Fig. 2 wherein one cylinder functions normally while another is shorted out of operation.

The invention has proved successful in solving the problem of excessive speeds of two-cycle engines under the conditions recited. Even

very powerful engines idle smoothly and quietly and at the requisite reduced speed when controlled in accordance with this invention.

I claim:

1. For the control of idling speeds of substantially load-free, two-cycle engines having valve-controlled intake manifolds, and spark plug ignition, the combination of a normally open vacuum-operated ignition-shorting switch, and a closed vacuum line operatively connected for the operation of said switch and leading thereto from said manifold for the closing of said switch when the vacuum in said manifold becomes excessive.

2. In a two-cycle internal combustion engine having an ignition system comprising a spark plug, a coil, and breaker points, said engine having a pre-compression chamber provided with an intake manifold and a valve controlling mixture admission to said manifold; the combination of a vacuum-operated switch including a housing with an atmospheric connection and a closed connection to said manifold, said housing having a diaphragm spanning the housing between the atmospheric connection and manifold connection aforesaid, means biasing the diaphragm toward the atmospheric connection to a normally retracted position, the diaphragm being yieldable toward the vacuum connection in opposition to said biasing means when the vacuum is excessive in the manifold, a grounded contact connected with the diaphragm to be moved from its retracted position to an advanced position, an insulated contact positioned to be engaged by the grounded contact in the advanced position of the latter, and an electrical connection from said insulated contact to said coil for the grounding of the coil when vacuum in the manifold exceeds the value required to establish a pressure differential across said diaphragm for the advance of the diaphragm to engage its grounded contact with said insulated contact.

3. The device of claim 2 in which said engine comprises a plurality of cylinders having individual ignition systems, only one of which is provided with vacuum-operated short-circuiting means recited in claim 2.

4. The device of claim 2 in which said engine comprises a multiple-cylinder engine in which the several cylinders have individual ignition systems, a plurality of said systems being respectively provided with vacuum-operated short-circuiting switches described in claim 2.

5. The device of claim 2 in which the engine comprises a multiple-cylinder engine, the several cylinders having individual ignition systems of which less than the total number of cylinders are provided with vacuum-operated

switches for short-circuiting their respective ignition systems, certain of said cylinders, including cylinders with and without said vacuum-operated short-circuiting switches, having a common exhaust discharge passage, wherein unburned mixture discharged therein as a result of the functioning of a short-circuiting switch will be diluted and scavenged with burned gases from a cylinder not controlled by such a switch.

5 6. In a two-cycle engine having a manifold intake, the combination with an ignition breaker including relatively movable insulated and grounded points, of a control switch having relatively insulated and grounded contacts, a lead electrically connecting the insulated breaker point with the insulated contact of said switch, means for maintaining said switch normally open, and means for effecting the closing of the control switch contacts to short circuit such breaker points when engine speed is excessive while the engine is substantially without load, said means comprising means responsive solely to relative variation in the air pressure in said manifold intake.

10 7. The device of claim 6 in which the control switch comprises a pressure switch having a housing, a diaphragm sub-dividing the housing into two chambers and biased toward one of them, the housing being vented whereby one of the chambers is subject to atmospheric pressure, a pressure connection to the other of the chambers, a contact button carried by the diaphragm and having an electrical ground connection, and an insulated contact carried by the housing in 15 the path of movement of said button in opposition to said bias whereby a pressure differential overcoming said bias will engage said contacts to ground the insulated contact, said insulated contact having an electrical connection with the insulated contact of said breaker for the grounding thereof when said pressure differential is established.

20 8. The device of claim 7 in which the engine has a throttle-controlled mixture intake passage, the pressure connection aforesaid comprising a duct leading from such passage to said other chamber, and said diaphragm being biased toward the vented chamber.
